UNITED STATES PATENT OFFICE.

ROBERT P. CUNNINGHAM, OF HOLYOKE, MASSACHUSETTS, ASSIGNOR TO INTERNATIONAL STEAM PUMP COMPANY, OF NEW YORK, N. Y., A CORPORATION OF NEW JERSEY.

SCREENING-MACHINE.

No. 891,821.

Specification of Letters Patent.

Patented June 30, 1908.

Application filed May 3, 1907. Serial No. 371,571.

To all whom it may concern:

Be it known that I, ROBERT P. CUNNINGHAM, a citizen of the United States, residing at Holyoke, county of Hampden, and State of Massachusetts, have invented certain new and useful Improvements in Screening-Machines, fully described and represented in the following specification and the accompanying drawings, forming a part of the same.

10 This invention relates to an improved screening machine, which is especially intended as a sand screen or riddler, although capable of use for other purposes, the especial object of the invention being to secure a better screening action than in previous sand screens, and further to provide a simple and durable construction capable of operating efficiently at a high speed and which shall be reliable in action and avoid danger of stop-
20 page.

For a full understanding of the invention, a detailed description of a sand screening machine embodying all the features of the same in their preferred form will now be given in connection with the accompanying drawings forming a part of this specification, and the features forming the invention then specifically pointed out in the claims.

In the drawings—Figure 1 is a side elevation, partly in section. Fig. 2 is a plan view partly in section. Fig. 3 is a vertical section of the screen actuating mechanism.

Referring to the drawings, A is the screen holder consisting of a circular frame receiving the removable screen B, and mounted upon arms C which are pivoted to their supports at 10 and pivotally connected to the screen holder at 11 so as to rock on the supports as the screen reciprocates. The pivot 40 10 is shown as a pivot shaft rocking in brackets 12 on triangular screen stand D which supports the engine by which the screen is actuated, but it will be understood that any other form of support for the rocking arms and 45 screen holder may be used.

The screen holder A is connected to the reciprocating piston rod 13 of piston e moving in motor cylinder E, the cylinder and piston forming a double acting direct acting reciprocating engine, which may be actuated by steam, compressed air or other suitable motor fluid. The motor fluid is supplied to the engine through ports 1, 2 and exhausted through cover 3, which are controlled by the 55 valve 6 shifted by the auxiliary piston 5 in

auxiliary cylinder F, which auxiliary piston is shown as connected directly to the valve 6, and controlled by the auxiliary valve 4 which controls the admission and exhaust of steam to opposite ends of the auxiliary piston 5, for 60 moving it in opposite directions, as usual in such constructions.

The auxiliary valve 4 is actuated by the valve rod 7 provided with the usual tappets 8 engaged by the block 9 on valve lever f, 65 so as to move the auxiliary valve in opposite directions to the movement of the piston e, at the ends of the engine stroke, as the block 9 engages one or the other of the tappets 8, the valve lever f being actuated from the piston rod 13. The piston rod 13 and valve rod 7 are supported and guided in guide 14 forming one end of the casing G, as shown.

The operation of the construction will be understood without detailed description, the shifting of the main valve 6 by the steam thrown piston 5, controlled by the auxiliary valve 4, securing a quick positive throw of the engine piston e, and a positive jerky movement of the screen B which, in connection 80 with the swinging movement of the arms C, secures a screening action, which in practice is found efficient and an important improvement on previous screening movements. The positive throw of the screen in both di- 85 rections by the double acting direct acting engine assures reliability of action and avoids danger of stoppage.

It will be understood that the invention is not to be limited to the particular form of 90 valve mechanism shown, nor to the detail form of other parts of the structure, but that modifications may be made without departing from the invention.

What I claim is:

1. The combination with a screen holder, of pivoted rocking supports for the holder, a stationary double acting direct acting engine having its piston connected to the screen holder for reciprocating the holder, a fluid 95 thrown valve for said engine, an auxiliary valve controlling the fluid supply for said fluid thrown valve, and connections between the auxiliary valve and the screen holder for positively operating the auxiliary valve 100 from and in unison with the screen.

2. The combination with a supporting frame, of a double acting direct acting engine rigidly mounted directly upon said frame, a screen holder mounted on pivoted 110

rocking supports at one side of the engine, the piston rod of the engine being connected directly to the screen holder, and valve devices for controlling the movements of the engine piston including a valve actuated positively from and in unison with the screen holder.

In testimony whereof, I have hereunto set my hand, in the presence of two subscribing witnesses.

ROBERT P. CUNNINGHAM.
